(57) **CLAIM**

The ornamental design for a dash cam, as shown and described.

DESCRIPTION

FIG. 1 is a top, front, left side perspective view of a dash cam showing my new design;

FIG. 2 is a top, rear, right side perspective view thereof;

FIG. 3 is a bottom, rear, right side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged portion view taken from the encircled portion labeled, "10," in FIG. 2;

FIG. 11 is an enlarged portion view taken from the encircled portion labeled, "11," in FIG. 4; and,

FIG. 12 is an enlarged portion view taken from the encircled portion labeled, "12," in FIG. 5.

The dash-dot-dash lines form the boundary of the enlarged portion view of FIG. 10 in FIGS. 2 and 10, the enlarged portion view of FIG. 11 in FIGS. 4 and 11, and the enlarged portion view of FIG. 12 in FIGS. 5 and 12 and form no part of the claimed design. The even dashed broken lines shown in the drawings are included for the purpose of illustrating portions of the dash cam that form no part of the claimed design.

1 Claim, 12 Drawing Sheets
